CLAIM

An ornamental design for vehicle snorkel, as shown.

DESCRIPTION

FIG. 1 is a front view;

FIG. 2 is a side view;

FIG. 3 is a top view; and,

FIG. 4 is a three dimensional view.

The broken lines shown in the drawings are for the purpose of illustrating portions of the article that form no part of the claimed design.

1 Claim, 4 Drawing Sheets

FIG. 1

FIG. 2

FIG. 3

FIG. 4
